UNITED STATES PATENT OFFICE

2,651,871

METHOD OF PAINTING AND DECORATING

Charles P. Lynden, Detroit, Mich.

Application May 21, 1953, Serial No. 356,439

3 Claims. (Cl. 41—26)

1

This application is a continuation-in-part of my co-pending application Serial Number 103,080, filed July 5, 1949, now abandoned.

This invention relates to a novel method of painting and decorating and more particularly to a method of stenciling walls and other surfaces in a plurality of colors.

It is the object of this invention to employ a plurality of stencils, each of which have cut-out portions which form a part of a composite design, and separately applying such stencils to a surface, and applying a different colored paint for each such stencil, said paint having the characteristic of spontaneously drying to a mat surface, after which another stencil is applied to the same surface with said stencil having a plurality of cut-out portions also forming a part of said composite design, and thereafter polishing or brushing without removing the respective paints through said last stencil to thereby achieve a gloss or sheen at the areas polished a two-tone color effect for each of the original colors used in the composite design.

It is the further object of this invention to provide multi-colored designs upon surfaces which can be effected in the minimum of time.

It is the further object of this invention to provide a simple process whereby designs in a plurality of colors may be applied to a surface such as a wall with a minimum of effort.

These and other objects will be seen from the following specification and claims in conjunction with the appended drawings, in which:

Figure 1 is a fragmentary front elevational view of a wall surface upon which a stencil is applied, and with the first color shown painted upon the surface through the openings in said stencil.

Figure 2 is a similar view with the first stencil removed and a second stencil applied to the same surface and with a second color shown painted upon the surface through the openings in said second stencil.

Figure 3 is a similar view but with a third stencil applied to the same surface and with the portions of the painted design showing through said stencil having been polished.

Figure 4 is a front elevational view of the composite multi-colored design produced by the process hereinafter described in detail; and

Figure 5 is a front elevational view of the stencil shown in Figure 3.

It will be understood that the above drawings illustrate merely one preferred embodiment illustrating the steps of the process herein described, and that other embodiments are contemplated.

2

within the scope of the claims hereafter set out.

The present method provides for the stenciling of multi-colored designs upon walls and other surfaces, and may be applied either to a plain or to a painted surface.

Referring to Figure 1, a wall 11 is fragmentarily shown, which for the purpose of this application is plain, but which could just as well be painted. The stencil 12, is preferably constructed of an oiled and shellacked paper which is approximately .010 of an inch in thickness. This stencil has been initially cut out at 13 to form a part of a composite design to be applied in multiple colors to said surface 11.

15 It is contemplated that almost any type of design or configuration may be cut out of the stencil blank to form a part of the composite design contemplated.

As the initial step in the present process, the 20 stencil 12 is placed over the surface 11 at a predetermined position and held in place with masking tape, for example, or may be held in place by hand.

As a next step, a preferably flat paint is applied to the surface 11 through the openings 13 in the stencil 12 to provide the painted portions 14, which as shown are green, for example.

Generally, any paint may be used which has the characteristic of spontaneously drying to a mat surface, which can be changed in appearance to show a degree of gloss or sheen if polished while in a partially set condition.

For example, any flat paint may be employed, or any paint which does not normally dry to give a glossy appearance. As the present method contemplates a polishing step to produce a sheen or glossy effect, normally those paints which dry to a shiny surface would not be employed, such as enamel or house paint.

40 A flat paint containing varnish and wax will produce a pleasing effect, such as the type of paint disclosed in United States Patent No. 2,125,237, dated July 26, 1938.

While the paint 14 may be applied with a brush, it has been found that it may be rolled onto the 45 surface 11 by a small carpet roller, stippler, or similar device. The roller is initially dipped into the paint of the desired color and consistency and is first rolled back and forth upon a newspaper, for example, to obtain an even distribution of color upon the roller. Thereafter, the paint is rolled onto the surface 11 through the silhouette or cut-out portions 13 formed within the stencil 12.

Stencil 12 is then removed and may be placed 50 in another previously planned position and the

same color can be rolled onto the surface 11, and this operation may be repeated for about a dozen or more placings, easily reached without changing ones operating position.

Thereafter and as the next step in the present process or method, a second stencil 15, preferably of paper, and with cut-out portions 16, is applied to the surface 11 being superimposed upon the original design achieved from the first stencil.

It must be remembered, however, that there should be a sufficient time interval elapsed before application of the second stencil 15 in order that the first applied paint will have become sufficiently set or is partially set.

Figure 2 illustrates the position of the stencil 15 over the design obtained from the stencil 12, said latter design being indicated in dotted lines by the numerals 14, corresponding to Figure 1. It is necessary that there be a proper registry of the design from stencil 15 with respect to the design of stencil 12, and for this purpose, some slight marking or indication may be necessary to assure the proper positioning of stencil 15, after which, it is properly secured in position with masking paper, for example or may be held in place by hand.

As a next step in the present method, a second color of paint of the same character, as for instance, red, is applied to a second roller and this paint is then rolled upon the surface 11 through the cut-out portion 16 of stencil 15 to achieve the painted designs 17 shown in Figure 2. Thereafter the stencil 15 is removed and may then be reapplied to each of the other designs which have been painted upon the surface 11 by the original positionings of stencil 12.

Now after sufficient time has elapsed so that this second application of color has set and is partially dry, a third stencil 18, normally larger than stencils 12 and 15 will be applied to the surface 11 and will be properly aligned with the initial design obtained from stencils 12 and 15.

This latter stencil 18 shown in Figure 5 is preferably constructed of Celluloid and has formed therein a series of cut-out portions 19 adapted to represent veins of leaves, petals of flowers, shadows, deeper edges or any other smaller markings that may be required to make all of the previously applied color designs show up in their natural forms.

As a next step in the present method, the multi-painted portions of the composite design are brushed or polished through the silhouetted portions 19 of stencil 18 to thereby produce a darker tone for each of the colors applied to the composite design in the polished areas.

This polishing is done by the application of friction to the painted surfaces, after said paint has partially set. Preferably, a brush having rather stiff bristles is used.

Normally the polishing will not take place until after the paint has set so that it has lost its original sheen. The brushing or polishing thus produces a glossy portion to the painted design, so that in effect for any one color you have produced a two-color effect.

The present method does not contemplate the obtaining of the two-color effect in itself as shown in United States Patent No. 2,082,050, dated June 1, 1937, but only the provision of such two-color effects for each of the colors initially applied to and forming a part of the composite design.

In other words, for every color of paint initially applied to the composite design, the final polish-

ing operation through stencil 18 will achieve double the number of colors in the final design, such as shown in Figure 4. It is understood that the polishing is such that the paint so polished is not removed.

It will be noted that polishing through stencil 18 shows the green portion 14 together with the glossy or shaded green elements 20 of a darker tone, which are indicated by darker shading. Furthermore, the red portions 17 which form a part of the design contain therein the glossy or second shade of red, i. e., elements 21 of a darker tone, which are also shown by heavier vertical shading.

Thus, while only the two colors red and green were applied to the design, the present method provides for the four color effect shown in Figure 4.

Naturally, the present method may be carried further by employing additional paper stencils of the type shown in Figures 1 and 2 and by using additional colors. The same result will follow in the final design inasmuch as there will be double the number of visible color effects produced.

The designs which may include murals, wall paper designs, wood carvings, scenic designs, landscapes, flowers, or any desired wall decorations, will be produced in multiple colored elements, and the entire design will have a long-lasting washable surface, and the time required for producing the multi-colored designs will be considerably less than the time normally required by other methods in producing multi-colored designs.

Having described my invention, reference should now be had to the claims which follow for determining the scope thereof.

I claim:

1. The method of painting and decorating walls and ceilings which comprises applying a stencil to such surface, applying a paint of one color to such surface through said stencil, said paint having the quality of spontaneously drying to a mat surface which can be changed to show a gloss if polished, permitting the paint to partially set, applying a second stencil to the same surface area, applying paint of the same character but of a second color to said surface through said second stencil, permitting the latter paint to partially set, applying a third stencil to the same surface area, and brushing the paints through the silhouette of said third stencil without removal of said paints to obtain a darker tone at the polished areas for each color of paint applied.

2. The method of painting and decorating a structural surface which comprises applying a stencil to such surface, the stencil being cut-out to outline part of a composite design, applying a paint of one color to said surface through said stencil, said paint having a quality of spontaneously drying to a mat surface which can be changed to show a gloss if polished, permitting the paint to partially set, applying a second stencil to said surface, which stencil is cut-out to outline another part of said design, applying paint of the same character but of another color to said surface through said second stencil, permitting the latter paint to partially set, applying a third stencil to said surface, which stencil is cut-out to outline another part of said composite design, and brushing the paints through the cut-out portions of said third stencil without removal of

said paint to obtain a darker tone at the polished areas for each color of paint applied throughout said design.

3. The method of painting and decorating a structural surface which comprises separately applying to a surface a plurality of stencils, each of which is cut-out to outline a part of a composite design, applying a different colored paint to said surface respectively through each of the cut-out portions of each of said stencils, said paint having the quality of spontaneously drying to a mat surface which can be changed to show a gloss if polished, permitting the paint to partially set, applying to said painted surface another

5 stencil whose cut-out portions outline another part of said composite design, and brushing the paints without removal thereof through the cut-out portions of said latter stencil to obtain a darker-tone at the polished areas for each of the colors throughout the complete design.

CHARLES P. LYNDEN.
